METHOD AND APPARATUS FOR
STRAIGHTENING HOUSINGSArmais Arutunoff, Bartlesville, Okla., assignor to
Reda Pump Company, Bartlesville, Okla., a cor-
poration of Delaware

Application November 4, 1937, Serial No. 172,758

4 Claims. (Cl. 153—52)

My invention relates to a method of straightening housings and more particularly to straightening housings for deep well pumps.

A deep well pump must necessarily be of comparatively small cross sectional diameter with respect to its length, in a deep well, for example, 5000 feet in depth. The limitation of the cross sectional dimension of the well casing, which is usually about seven inches, necessitates the employment of a large number of stages. The stages may vary from 108 in number to 195 in number, depending upon the type of impeller employed. This necessitates the provision of a pump housing upwards of 20 feet in length. In a centrifugal pump, for example, the construction will be comprised of alternate diffuser housings and impellers, the impellers being driven by a shaft extending therethrough. If the pump housing is deflected, that is, if the axes of the impellers are not in substantial alignment, the deflection of the shaft will be such as to destroy the unit after a short interval of pumping. If the deflection is great, the added load may cause overheating of the motor and consequent destruction.

One object of my invention is to provide a novel method of straightening a pump housing of great length with respect to its diameter.

Another object of my invention is to provide a method for straightening elongated tubular housings.

Another object of my invention is to provide a novel apparatus for straightening elongated housings.

Other and further objects of my invention will appear from the following description.

In the accompanying drawing which forms part of the instant specification and are to be read in conjunction therewith and in which like reference numerals are used to indicate like parts in the various views;

Figure 1 is an elevation, with parts in section, of one form of apparatus embodying my invention and capable of carrying out the method of my invention.

Figure 2 is a sectional view, drawn on an enlarged scale, taken on a line 2—2 of Figure 1.

Figure 3 is a view, drawn on an enlarged scale, taken along the line 3—3 of Figure 1.

Figure 4 is a sectional view drawn on an enlarged scale, taken along the line 4—4 of Figure 1.

Figure 5 is a sectional view taken along the line 5—5 of Figure 4.

More particularly referring now to the drawing, the tubular housing to be straightened is indicated by the reference numeral 1. It is sup-

ported at one end for rotation by a bearing 2, mounted on a suitable support 3 which is in turn supported by the body 4 of a lathe. The head stock 5 of the lathe carries a chuck 6 which clamps the other end of the housing 1 which is to be straightened. The carriage 7 of the lathe supports a universal joint 8 which supports a rod 9. A support 10 carries a gauge 11 which is provided with a gauge finger 12. Within the tubular housing 1, to be straightened, I position an expanding anvil comprising external members 13 and an internal expanding member 14. The members 13 are provided with bores 15 through which extend a plurality of stud bolts 16. The bolts are of smaller diameter than the bores 15. The threaded ends of the stud bolts are seated in a ring 17, to which is secured a tube 18 which extends through the head stock of the lathe and is supported by a pedestal 19, as can readily be seen by reference to Figure 1. The external anvil members 13 are supported between the ring 17 and the ring 20 as can readily be seen by reference to Figure 2. The members 13 are internally tapered and the member 14 is tapered in an opposite direction. Secured to the member 14 is a rod 21 which extends through the tube 18. The outer end of the rod 21 is threaded at 22 and is provided with a nut 23 and a washer 24 which bears against the end of tube 18. It will be readily apparent that tube 18, being secured to the ring 17, and rod 21 being secured to the member 14, that, upon setting up of the nut 23, the member 14 will tend to be forced into the ring of members 13. Due to the fact that the bores 15 are of larger diameter than the bolts 16, the members 13 will tend to move radially outward, thus clamping the expanding anvil within the tube 1.

The other end of member 14 is provided with a seat 25 in which is adapted to seat the pointed end 26 of the rod 9.

The universal joint 8 comprises a ring 27 which is supported by a standard 28 carried in a socket formed in the member 29 of the carriage 7. The ring 27 carries pivot points 30 and 31 which pivotally support a ring 32. The ring 32 carries pivot points 33 and 34 which pivotally support a ball member 35. The ball member is provided with a bore 36 through which the rod 9 extends. The end of the ball member is provided with a threaded portion 37 which is in turn provided with cutaway portions 38, to provide for a flexing movement. The threaded portion is tapered and adapted to receive a nut 39 which, when screwed to the left as viewed in Figure 5, will clamp the rod 9 in position. The gauge 11 may be of any

suitable type, which will indicate the extent of movement of the gauge finger 12.

- In operation, the expanding anvil is positioned within the housing 1 to be straightened. The 5 pointed end 26 of the rod 9 is seated in the seat 25 of the member 14 and the clamping nut 39 operated to clamp the rod in position, supported by the universal joint 8. The gauge finger 12 contacts a portion of the rod 9. The head stock 10 5 is then rotated by means of a suitable belt drive (not shown) acting through one of the drive pulleys 40. If the housing 1 is deflected, that is, if the portion of the housing to which the expanding anvil is secured is not in exact alignment with 15 the ends of the housing, the seat 25 will describe a circle depending upon the displacement or deviation of that portion of the housing to which the expanding anvil is secured. This will cause the outer end 41 of the rod 9 to describe a circle. 20 When the low point of the housing is uppermost, the end 41 of the rod 9 will be highest, thus moving gauge finger 12 into the gauge the greatest distance and indicating the greatest throw.

Referring now to Figure 2, it will be observed 25 that a construction line 42 has been drawn from which it will be readily observed that the housing 1 is deflected downwardly, that is, the low point or the concave portion of the housing is uppermost. An observer at the gauge may stop the 30 rotation of the housing at the point of greatest deviation, by any suitable control means (not shown).

One would think that, in order to straighten the housing, hammering should take place at the 35 high point. The contrary, however, is the fact. An electric hammer 42' is provided and the peening takes place in the vicinity of the point indicated by the arrow 43 in Figure 2. During peening, the metal of the housing is hammered 40 on the expanding anvil, elongating the upper metal surface of the housing longitudinally. It is understood, of course, that during hammering, or peening, the electric hammer 42' is moved about slightly so that the peening is spread over 45 a slight area adjacent the arrow 43, that is, the low point or concavity. The compression and expansion of the metal lengthens the dimension and warps the housing back into line. The extent of peening, of course, is governed by the 50 extend of deviation. After peening, a short interval, the housing is again rotated and the gauge watched. When the center of the expanding anvil is exactly in line with the axis of the housing 1, no deviation of the outer end of 55 the rod 41 will occur, during rotation, and the housing is straight at this point. When this has been achieved, the clamping nut 39 is loosened, the nut 23 is backed off and the expanding anvil moved to another position adjacent the point 60 which has been straightened, the anvil re-expanded, the rod 9 re-clamped and the operation repeated.

It is understood, of course, that the process may be practiced to any desired extent, depending upon the accuracy desired. It is possible, by means of my method, to substantially obtain accurate alignment of an elongated housing. 5 Frequently, deviations may occur in two directions. When this happens, the point of greatest deviation is first corrected and then the minor deviation or deviations are corrected until alignment is achieved. 10

It will be clear to those skilled in the art that I have accomplished the objects of my invention. I am enabled to straighten elongated housings in general. The straightening action is accomplished by elongating the metal on the low side 15 of the housing, that is, when a housing is deviated or bowed, the peening takes place upon the concave or low side, in order to elongate the metal on this side, which elongation of metal straightens the deviation. 20

Having thus described my invention, what I claim is:

1. A method of straightening a bowed metal tubular housing including the steps of positioning an anvil within said housing and peening the 25 metal only upon the concave side of the housing and upon said anvil to elongate the metal of the housing sufficiently to straighten the housing.

2. A method of straightening an elongated tubular metal housing including the steps of 30 successively positioning an anvil within said housing and peening the metal of said housing only at successive concave places therealong against said anvil to elongate the metal of the housing at said concave places sufficiently to 35 straighten the housing.

3. A method of straightening a tubular housing including the steps of positioning an anvil within said housing, determining the eccentricity 40 of said housing at said anvil, peening the metal of the housing wall only on the concave side of the point of greatest eccentricity against said anvil to elongate the metal of said housing at said concave side, and repeating the above steps successively at a plurality of separated points 45 along the length of said housing to straighten the housing.

4. In an apparatus for straightening tubular housings, an anvil adapted to be positioned within said housing, means for expanding said anvil, means for rotating said housing, a gauging rod, means for universally supporting said rod at a point intermediate the ends thereof, means for positioning one end of said rod within said housing at the axes thereof in the vicinity of 50 said anvil, a gauge positioned without said housing for determining the amplitude of motion of the other end of said rod, and means for peening the exterior of said housing. 55
